REFRIGERATING APPARATUS

George C. Pearce, Dayton, Ohio, assignor to General Motors Corporation, Dayton, Ohio, a corporation of Delaware

Application May 26, 1939, Serial No. 275,959

17 Claims. (Cl. 200—83)

This invention relates to refrigerating apparatus and more particularly to refrigerator control means.

It is an object of my invention to provide an inexpensive, accurate, reliable low differential control capable of providing uniform trouble free, results for a long period of time.

Heretofore it has been difficult to provide a switch mechanism capable of carrying heavy currents on a low differential. It has been necessary to use either an expensive magnet type switch, a pilot and relay switch or a switch of rather large dimensions. One of the difficulties has been to provide a satisfactory form of snap acting device, which has a low differential and high current carrying capacity and which is durable and has a long life.

It is an object of my invention to provide a control means with an improved toggle device which has these desirable characteristics and provides an inexpensive form of low differential toggle having a high current carrying capacity.

It is another object of my invention to provide a toggle switch which will not bounce or chatter, which has little friction or wear, and which is simple and reliable.

Heretofore a differential of ordinary controls has been adjusted by providing a floating member held against a stop by a single spring, which floating member is picked up by the movement of the control device. I have found that when the spring has its tension reduced to a very small amount that such a device gives unreliable results so that a small adjustable differential cannot be obtained.

It is an object of my invention to provide a control in which differential adjustment means is provided which can add to the minimum differential provided by the toggle device any added amount of differential from zero to the maximum desired differential.

It is still another object of my invention to provide an improved form of spring hinge construction which will carry a relatively heavy load with a thin spring and which holds the parts permanently in place so that they will not be moved whenever the control is moved about.

Further objects and advantages of the present invention will be apparent from the following description, reference being had to the accompanying drawings wherein a preferred form of the present invention is clearly shown.

In the drawings:

Fig. 1 is a view partly in elevation and partly

in section of one form of my improved control means taken on the line 1—1 of Fig. 4;

Fig. 2 is a sectional view taken along the lines 2—2 of Fig. 4;

Fig. 3 is a sectional view taken along the lines 3—3 of Fig. 1; and

Fig. 4 is a sectional view taken along the lines 4—4 of Fig. 1.

Briefly, I have shown a refrigerator control switch mechanism with a high pressure cutout. The switch includes a novel toggle mechanism providing a low differential and a high current carrying capacity. The switch mechanism and the high pressure cutout mechanism incorporate an improved type of spring hinge construction in which the supporting member overlaps the lever member with the spring member in between the overlapping members so that the overlapping members carry the shear stress and prevent the shear stress from falling upon the spring member. I have also provided an improved form of differential control involving opposed springs which act in opposite directions upon the floating pick-up member.

The switch mechanism

Referring now to the drawings and more particularly to Fig. 1, there is shown a control base 20 formed of pressed steel with a heavy flange 21 around its edges. This base 20 supports a flexible metal bellows 22 which is fastened to the base 20 by a nut 24 which is threaded onto the neck 26 provided upon the lower end of the bellows 22. The bellows 22 and its neck 26 are preferably connected by capillary tubing 28 to a source of pressure such as a thermostat bulb or some pressure connection which will supply the pressure for operating the control. The bellows 22 is provided with a conical point 30 at its upper end which bears against the main lever 32 of the switch mechanism. This main lever 32 is pivoted to a support 34 mounted upon a platform 36 which is supported at one end of the base by the posts 38. This platform 36 extends substantially across the base 20 and has feet portions extending down at one edge to the base for providing a firm support as is best shown in Fig. 2.

The main lever and spring hinge

The support 34 supports a leaf spring 40 over which is a supporting plate 42 which is held in place by a rivet head formed on top of the support 34. The rivet head holds the support plate 42 and one end of the leaf spring 40 firmly in place. The support plate 42 overlaps the adja-

cent end of the main lever 32, so that the shear stress at the hinge which is provided by the pressure the bellows 22 is carried not by the leaf spring 40 but by the supporting plate 42. This makes it possible to make the leaf spring 40 very thin so that it is very flexible and will not affect the movement of the main lever 32. The other end of the leaf spring 40 is riveted to the upper face of the main lever 32 as is clearly shown in Figs. 1 and 4.

This leaf spring hinge connection is superior to prior types of spring hinge connections since the spring member itself carries very little stress and thus can be made very thin. Also the effective spring length, that is, the unfastened portion of the spring can be made long so that the bending stresses upon the leaf spring are small and any possibility of breakage of the leaf spring is thereby avoided. As pointed out above the overlapping of the end of the main lever 32 by the supporting plate 42 prevents shearing stress from being applied to the leaf spring 40. In reality, the only substantial stress upon the leaf spring 40 is a very light pull in direct tension. This form of hinge is far superior to a knife edge or a pinned hinge since both knife edges and pinned hinges have a certain amount of friction and knife edges are apt to become easily dislodged under rough handling.

It should be noted that the supporting platform 36 has an aperture which receives the conical point of the bellows 22. The platform 36 overlies the upper end of the bellows 22 and serves as a stop to prevent damage to the bellows 22 by excessive internal pressure.

The toggle and contact mechanism

The other end of the main lever 32 is provided with a connecting member 44 of insulating material. This connecting member 44 may be molded directly onto this end of the main lever. Fastened to the end portion of the connector member 44 is a two-arm spring support 46 to which is hooked one end of each of the two light tension toggle springs 48. The other end of each of the toggle springs 48 is hooked to the end of a relatively rigid arm 50 which is provided with a pair of ears 52 for this purpose. These ears 52 are provided at the end of wings or projections so as to hold the toggle springs 48 on either side of the arm 50 but in substantial alignment with the arm 50. This end of the arm 50 moves between stops, one of which is in the form of an L-shaped stop 54 which is riveted to the top of a conductor post 56.

This conductor post 56 at its lower end is riveted to an electrical conductor strip 58 to which an electrical conductor may be fastened by means of a screw threaded into the outer end of the strip. Also fastened to the top of the conductor post 56 beneath the stop 54 is a very thin leaf spring 60. The upper surface of this leaf spring 60 serves as the second stop for the adjacent end of the rigid arm 50 which thus is permitted to move between the stop 54 and the leaf spring 60. The other ends of the leaf spring 60 and the rigid arm 50 are riveted together by the electrical contact member 62 in which the contact proper forms the head of the rivet. The rigid arm 50 is provided with an offset portion 64 adjacent the riveted portion so as to allow the center line of the toggle springs 48 to move across the plane of the leaf spring 60.

This permits the leaf spring 60 to bend freely in between the contact portion and the conduct-

ing post 56 which serves as an anchor for the leaf spring 60. The contact 62 is adapted to make contact with the contact post 66 which is riveted onto the conductor strip 68 to which another conductor may be fastened by a suitable screw. This contact post 66 of course serves as a stop for the movement of the contact 62 in one direction. The movement of the contact 62 into open position is limited by a small set-screw 70 which is held in an insulating arm at 72 projecting from the wall of an insulating casing 72 which supports the toggle mechanism of the contact mechanism. This insulating casing 72 has a downwardly extending portion 74 which is fastened to base 20 and holds the insulating casing 72 in proper relation to the bellows 22 and the main lever 32.

The toggle mechanism is shown with the contact 62 in the open position. The toggle springs 48 are below the plane of the leaf spring 60. When this control is used in a refrigerating system, the compressor will be idle when the contacts are open and the temperature and pressure will increase in the bellows 22 during the said period. This will cause the bellows 22 to expand and raise the main lever 32. The raising of the main lever 32 will cause one end of the toggle spring 48 to cross the plane of the leaf spring 60 and when this end of the toggle spring is carried sufficiently far, the toggle mechanism will snap the contacts 62 down onto the top of the contact post 66. At this time the other end of the rigid arm 50 will move from its position on top of the leaf spring 60 to a position near to or against the stop 54. As long as the main lever 32 moves within normal limits, the stop 54 is unnecessary. This arrangement will cause the contact 62 to be held closed with considerable contact pressure.

I find with this toggle mechanism, that there is no bouncing of the contacts when the switch is closed. This prevents the burning of the contacts and aids in the carrying of heavy initial currents and is a factor in obtaining long life out of the contacts. The closing of the contacts will cause the refrigerating system to operate and to reduce the pressure within the bellows 22. This reduction in pressure within the bellows 22 will lower the ends of the toggle springs 48 which are connected to the main lever 32. This will also pull the ears 52 gradually downwardly so that while the contacts are closed, the arm 50 gradually pivots itself upon the fulcrum of the pivot formed by the contact 62 resting upon the contact post 66. This pivoting will continue until the tripping point is reached after which the contact will snap to the open position with the rivet head against the stop screw 70. This pivoting of the arm during engagement of the contacts causes the contacts to engage at one point upon closing and to be in contact at another point when the switch opens. There also appears to be a beneficial wiping action provided between the contacts by the pivoting of the rigid arm 50 during the time that the contacts are in engagement. I find that this mechanism makes it possible to carry comparatively large currents without the burning of the contacts and in fact makes it possible for the contacts to have a long life. There is very little, if any, arcing at the contacts.

Only one set of contacts are required in this arrangement. The leaf spring 60 serves as the conductor between the movable contact and the binding post so that no pig-tail connections are

required and no shunt contacts need be provided. There is substantially no friction to this form of toggle mechanism and also substantially no wear so that the switch should provide uniform operating conditions throughout its life. The leaf spring 30 is held in tension at all times and therefore may be made very thin. By making this leaf spring thin there is less bending stress in the leaf spring and the leaf spring will have a lesser spring force so that a very low differential is incorporated in this toggle mechanism. The only compression member in the mechanism is the rigid arm 50 which can be made sufficiently thick to prevent it from being bent under any normal stress. The stress upon the rigid arm 50 is not great since it is required only to withstand the stress imposed by the toggle springs 48. It has been found that a relatively large amount of current can be carried even though the toggle springs 48 are comparatively weak. The weight of the parts of the toggle mechanism is very small so that inertia effects will be minimized. This probably accounts for the fact that this toggle mechanism can provide a relatively large current carrying capacity with a relatively small differential and a relatively small contact pressure.

The range adjustment

The movement of the main lever 32 is controlled by a main spring 80 which is carried at its lower end by a spring retainer 82 provided with the conical point which rests in a notch provided in the upper face of the lever 32. The upper end of the spring 80 is supported by a spring retainer 84 which is threaded onto an adjusting screw 86. This adjusting screw 86 is rotatably mounted within an inverted U-shaped bracket 88 which has its lower ends fastened to the platform 36. The upper end of the screw 86 is provided with a two-part head provided with a bearing in the bracket 88 located between the two parts of the head. These two parts of the head are rigidly held together by a threaded connection which is locked in place by riveting the threaded end. The head of the screw is provided with a screw-driver slot for adjustment. The upper spring retainer 84 is provided with a projection 90 which extends into a vertical slot provided in the side wall of the bracket 88 so as to guide the retainer 84 and to prevent its rotation and also to serve as an indicator of the tension of the main spring 80. The position of the indicating projection may be calibrated and an adjustable scale 92 may be provided upon the outer face of the bracket 88 so that the setting of the switch will be indicated in the form of pound pressure or degrees.

The differential adjustment

The operation of the main lever 32 is also controlled by an improved form of differential adjustment. Heretofore such a differential adjustment has been provided by a floating member held against a stop by a spring and located so it will be engaged by the lever during a portion of its movement. It has been found that when very low differentials are desired, that is, a differential which is substantially equivalent to the differential provided by the toggle mechanism, that such a differential adjustment gives erratic results. This is probably due to the fact that considerable slack is provided when the spring is loosened sufficiently to reduce the differential to a minimum. I have provided a differential

adjustment which does not become slack or loose at minimum differentials and which will provide extremely small and very accurate additions to the differential provided by the snap acting mechanism.

In order to do this I have provided a floating member 94 which is provided with upper and lower threaded portions. A tension coil spring 96 is threaded onto the lower threaded portion and extends downwardly to the base where it is threaded onto a threaded stud anchor 98. The floating member 94 is provided with a stop in the form of a set-screw 102 extending upwardly from the base within the lower spring 96. The upper end of this set-screw has a conical point which normally rests in a notch in the bottom of the floating member 94. The upper threaded portion of the floating member 94 receives the lower end of the upper tension coil spring 104 which has its upper end connected to the outer threaded portion of the differential adjusting nut 106 which is threaded onto the differential adjusting screw 108. The head of the differential adjusting screw 108 rests upon the top of the inverted U-shaped bracket 88.

The differential adjusting nut 106 is provided with an indicating arm 110 which rides within a slot in the side wall of the bracket 88. This indicating arm, like the indicating arm 90, prevents the rotation of the nut 106 and also cooperates with the scale member 112 which is calibrated to indicate the differential adjustment provided by any position of the differential adjusting nut 106. In this differential adjustment the spring 90 is provided with sufficient tension to provide more than the maximum differential desired. The upper spring 104 is provided with as much tension as is desired in order to reduce the amount of differential provided by the lower spring 96.

It will be understood that if the tension of the upper spring 104 is so adjusted that it is equal to the tension of the lower spring 96 that substantially no differential will be provided by the floating member 94. Under such conditions the floating member 94 will be lifted off its stop screw 102 by the tension of the spring 104 and the floating member 94 will be raised so that the lever 32 will be free to move without contacting the floating member 94. It should be noted that the lever 32 is provided with a notch which receives the reduced portion of the floating member 94 between the two threaded portions which support the adjacent ends of the upper and lower springs. The movement of the main lever 32 between opening and closing positions is less than the distance between the two threaded portions of the floating member 94 so that the main lever may operate freely without contacting the floating member. It should be noted that in this minimum differential position that there is no slack in the differential adjusting mechanism and there is no possibility that any erratic results can be caused by the differential adjusting mechanism.

As it is desired to increase the differential, the tension of the upper spring 104 is gradually reduced so that the main lever 32 will only leave the floating member 94 a very small distance, such as a few thousandths of an inch so as to provide an extremely small differential to be added to the differential of the toggle mechanism. At this time the floating member will remain off its stop screw 102. As the tension of the upper spring 104 is reduced to provide greater differential, the floating member 94 will gradually move down-

wardly because of the greater margin of force that the lower spring 96 will have over the weakened upper spring 104. This will increase the distance that the floating member 94 must be lifted by the main lever 32 and this will increase the added differential provided by the differential adjustment. Further decreases in tension of the upper spring 104 will cause the floating member to gradually approach the stop screw 102 and finally cause it to rest normally upon the stop screw 102. This will provide a gradually increased differential which may be increased until the tension of the upper spring 104 has been reduced to the minimum tension necessary to hold the differential adjustment in place.

Thus the differential adjustment does not depend upon a single spring but depends upon the difference in tension between the lower and the upper springs. This provides a superior differential adjustment throughout the entire range of differential settings desired.

The high pressure cutout mechanism

At the side of the switch mechanism thus far described I have provided a high pressure cutout mechanism which acts upon the toggle mechanism to open the contacts under dangerous conditions. In order to do this I have provided an internal bellows type of diaphragm operating member 120 which has its neck portion 122 fastened to the base by a nut 124. The neck 122 is connected to capillary tubing 126 which is preferably connected to the high pressure portion of a refrigerating system. The internal bellows operates a plunger provided with a conical upper end which engages a notch in the lower face of the main lever 130 which is provided with an overlapping type of spring hinge connection like that described for the main lever 32. The supporting plate 132 overlaps the end of the main lever 130 and between the overlapping end of the main lever and the supporting plate 132 there is fastened the leaf spring 134 which is fastened to the top of the main lever 130 and beneath the bottom of the supporting plate 132. As mentioned before the overlapping of the lever and the support plate takes the shear stress upon the hinge joint and allows the leaf spring to carry only the direct tension and other minor stresses.

The free end of the main lever 130 is provided with a double toggle snap acting mechanism including a secondary lever 136 pivoted to the end of the main lever by a knife edge construction and connected at its opposite end to a tension toggle spring 138 which is connected at its opposite end to the operating lever 140 of the high pressure cutout mechanism. This operating lever 140 is pivoted upon the pin 142 and is provided with notches for limiting the movement of the free end of the secondary lever 136. The lever 140 is normally held against a stop screw 144 by the toggle spring 138. The toggle mechanism together with the main spring 146 which opposes the upward movement of the plunger within the member 120 prevents the operation of the high pressure cutout mechanism under normal conditions and serves to hold the lever 140 against its stop screw 144.

The main spring 146 is held at its lower end by lower spring retainer 148 which has a conical point which rests in a notch upon the upper face of the main lever 130. Its upper end is retained by an upper spring retainer 150 threaded onto an adjusting screw 152 which is provided with a two-part head rotatably mounted in an aperture 70

provided upon the top portion of the bracket 38.

When a dangerously high pressure exists in the high pressure portion of the refrigerating system the tension of the main spring 146 and the toggle spring 138 will be overcome and the lever 140 will move downwardly away from its stop screw 144. This lever 140 is provided with an arm 154 of insulating material which extends over through a notch in the wall of the insulating casing 72 into the interior thereof. The extreme end of this arm overlies the end of the rigid arm 50 provided with the ears so that when the lever 140 moves downwardly this arm 154 will move the rigid arm downwardly so as to cause the contact 62 to be lifted away from the contact post 66 to stop the operation of the refrigerating system. When the high pressure in the high pressure portion of the system is reduced sufficiently, the main spring 146 will return the double toggle snap acting mechanism and the operating arm 140 to its ineffective position against the stop screw 144 to permit the switch contact 62 and its toggle mechanism to operate normally.

25 While the mechanism has been described as a refrigerator control switch, it obviously has other uses such as temperature and pressure controlled switches for other purposes and valves.

I claim:

30 1. A control means including a substantially rigid lever member, a substantially rigid supporting member overlapping one end of said lever member, leaf spring means extending between and in contact with the adjacent surfaces of the

35 overlapping portions of each of said members, said leaf spring means being connected to said members, a control device operated by said lever member, and operating means applied to the lever for moving the lever and for holding the 40 leaf spring means against the supporting member.

2. A control means including an operating means having a reciprocating movement, a control device operated by the reciprocating move-

45 ment of said operating means, snap acting means for controlling the movement of said operating means, a differential adjustment means comprising opposed spring means, an engaging means acted upon by said opposed spring means and located in a portion of the path of movement of a

50 portion of the operating means for engaging and disengaging said portion of the operating means in one portion of its reciprocating movement, a stop means for normally holding said engaging 55 means in a particular portion of the path of movement of said portion of the operating means and for limiting the movement of the engaging means in one direction, and means for adjusting the tension of one of said spring means.

60 3. A control means including an operating means, a flexible metal strip supported in cantilever fashion, a relatively rigid member having one portion fastened to said flexible metal strip at a point remote from said anchorage, said

65 member extending from said point toward the anchorage of said strip, and spring means connecting said operating means and a point upon said rigid member adjacent said anchorage for moving the flexible strip with a snap action and for maintaining a tension upon said strip.

4. A control means including an operating means, a flexible metal strip supported in cantilever fashion, a relatively rigid member having one portion fastened to said flexible metal strip 75 at a point remote from said anchorage, said

member extending from said point toward the anchorage of said strip, spring means connecting said operating means and a point upon said rigid member adjacent said anchorage for moving the flexible strip with a snap action and for maintaining a tension upon said strip, and means for limiting the movement of the flexible strip.

5. A control means including an operating means, a flexible metal strip supported in cantilever fashion, a relatively rigid member having one portion fastened to said flexible metal strip at a point remote from said anchorage, said member extending from said point toward the anchorage of said strip, spring means connecting said operating means and a point upon said rigid member adjacent said anchorage for moving the flexible strip with a snap action and for maintaining a tension upon said strip, and electrical contact means carried and operated by said strip.

6. A control means including an operating means, a flexible metal strip supported in cantilever fashion, a relatively rigid member having one portion fastened to said flexible metal strip at a point remote from said anchorage, said member extending from said strip toward the anchorage of said strip, and spring means connecting said operating means and a point upon said rigid member adjacent said anchorage for moving the flexible strip with a snap action and for maintaining a tension upon said strip; said spring means being in the form of a tension coil spring.

7. A control means including an operating means, a flexible metal strip supported in cantilever fashion, a relatively rigid member having one portion fastened to said flexible metal strip at a point remote from said anchorage, said member extending from said point toward the anchorage of said strip, spring means connecting said operating means and a point upon said rigid member adjacent said anchorage for moving the flexible strip with a snap action and for maintaining a tension upon said strip, an electrical contact fastened to the strip adjacent the connection between the strip and the member, a second contact, and a stop means for limiting the separation of said contacts.

8. A control means including a substantially rigid lever member, a substantially rigid supporting member overlapping one end of said lever member, leaf spring means extending between and in contact with the adjacent surfaces of the overlapping portions of each of said members, means for connecting the leaf spring means to each of said members, the adjacent surfaces of the overlapping portions of each of said members being separated only by said leaf spring means, a control device operated by said lever member, and means for applying a force to said lever member adjacent said leaf spring means substantially at right angles to said adjacent surfaces in a direction to hold the overlapping portions of said rigid members together with the leaf spring means held tightly between said overlapping portions.

9. A control means including an operating means having a reciprocating movement, a control device operated by a reciprocating movement of said operating means, a differential adjustment means comprising an engaging means located in a portion of the path of reciprocating movement of a portion of the operating means for engaging and disengaging said portion of the operating means in one portion of its reciprocating

movement, a plurality of tension springs each having an end connected to said engaging means with their opposite ends extending in different directions from the engaging means, anchoring means for said opposite ends of said springs, a stop means for normally holding said engaging means in a particular portion of the path of movement of said portion of the operating means and for limiting the movement of the engaging means in one direction, said springs normally being tensioned to hold the engaging means against said stop means when the engaging means is disengaged from the operating means.

10. A control means including an operating means having a reciprocating movement, a control device operated by a reciprocating movement of said operating means, a differential adjustment means comprising an engaging means located in a portion of the path of reciprocating movement of a portion of the operating means for engaging and disengaging said portion of the operating means in one portion of its reciprocating movement, a plurality of tension springs each having an end connected to said engaging means with their opposite ends extending in different directions from the engaging means, anchoring means for said opposite ends of said springs, a stop means for normally holding said engaging means in a particular portion of the path of movement of said portion of the operating means and for limiting the movement of the engaging means in one direction, said springs normally being tensioned to hold the engaging means against said stop means when the engaging means is disengaged from the operating means, said engaging means being free of support except for the springs and stop means, and means for adjusting the location of the anchorage of one of said spring means.

11. A control means including an operating means having a reciprocating movement, a control device operated by a reciprocating movement of said operating means, a differential adjustment means comprising an engaging means located in a portion of the path of reciprocating movement of a portion of the operating means for engaging and disengaging said portion of the operating means in one portion of its reciprocating movement, a plurality of tension springs each having an end connected to said engaging means with their opposite ends extending in different directions from the engaging means, anchoring means for said opposite ends of said springs, a stop means for normally holding said engaging means in a particular portion of the path of movement of said portion of the operating means and for limiting the movement of the engaging means in one direction, said springs normally being tensioned to hold the engaging means against said stop means when the engaging means is disengaged from the operating means, said engaging means being free of support except for the springs and stop means, and means for adjusting the location of the anchorage of one of said stop means.

12. A control means including an operating means, a supporting means, a first member provided with a first connection connecting to said supporting means, a second member, said first member being provided with a second connection remote from said first connection connecting with said second member, and spring means connecting said operating means and a portion of said second member adjacent said first connection.

13. A control means including an operating

means, a supporting means, a first member provided with a first connection connecting to said supporting means, a second member, said first member being provided with a second connection remote from said first connection connecting with said second member, spring means connecting said operating means and a portion of said second member adjacent said first connection, said spring means acting in such a direction to exert a tension upon said first member between its connections.

14. A control means including an operating means, a supporting means, a first member provided with a first connection connecting to said supporting means, a second member, said first member being provided with a second connection remote from said first connection connecting with said second member, spring means connecting said operating means and a portion of said second member adjacent said first connection, one of said members being in the form of a flexible resilient metal strip.

15. A control means including an operating means, a supporting means, a first member provided with a first connection connecting to said supporting means, a second member, said first member being provided with a second connection remote from said first connection connecting with said second member, spring means connecting said operating means and a portion of said second member adjacent said first connection, one of said members being in the form of a flexible resilient metal strip.

and electrical contact means adjacent to and operated in conjunction with the movement of said second connection.

16. A control means including an operating means, a supporting means, a first member provided with a first connection connecting to said supporting means, a second member, said first member being provided with a second connection remote from said first connection connecting with said second member, spring means connecting said operating means and a portion of said second member adjacent said first connection, one of said members being in the form of a flexible resilient metal strip.

17. A control means including an operating means, a supporting means, a flexible strip anchored to said supporting means and extending in cantilever fashion therefrom, and a double-back-type connecting means connecting said operating means and the free end portion of said flexible strip, said connecting means including a first portion rigidly connected to said free end portion of said flexible strip extending generally toward the anchoring point of said strip and merging adjacent the anchoring point with a second portion extending generally in the opposite direction to its connection with said operating means, one of said portions including spring means.

GEORGE C. PEARCE.
